His ATTORNEY,

UNITED STATES PATENT OFFICE.

THOMAS J. SMITH, OF BROOKLYN, NEW YORK, ASSIGNOR TO THE E. S. GREELEY & COMPANY, OF CONNECTICUT.

ELECTRO-MEDICAL APPARATUS.

SPECIFICATION forming part of Letters Patent No. 403,492, dated May 14, 1889.

Application filed February 19, 1889. Serial No. 300,429. (No model.)

To all whom it may concern:

Be it known that I, THOMAS J. SMITH, of Brooklyn, county of Kings, State of New York, a citizen of the State of New York, have invented certain new and useful Improvements 5 in Electro-Medical Apparatus, of which the following is a full, clear, and exact description, reference being had to the accompanying drawings, forming part of this specification.

10 My invention relates to an apparatus for the generation and application of electro-magnetism; and my invention consists in the parts and devices and their combinations herein-after described, and as more particularly and 15 at length recited in the claims.

Figure 1 is a plan of an electro-medical apparatus containing my invention. Fig. 2 is a similar view of the same, showing the parts in different relative positions to those exhibited in Fig. 1. Fig. 3 is an inverted plan of 20 my improved sliding base. Fig. 4 is a vertical central section of the apparatus on the line xx , Fig. 2, the cell being shown in full lines; and Fig. 5 is a front end elevation of the 25 apparatus when open.

A is the galvanic cell or battery. B is the inclosing-case of the apparatus. Within the case I construct the cell-chamber B' by means of a partition, b, extending laterally of the case near its forward end and reaching vertically from the case-bottom toward the top to the height of the cell, as shown, and I then cover the upper end of this chamber with a lid or roof, b', which slides 35 horizontally into the case-walls in ways b² provided therein. Apertures, as at b³, are provided in the lid for the passage of the pole-wires a a' of the battery. I thus inclose the battery in a separate and distinct chamber 40 within the apparatus-case, so that dust and other extraneous matter are excluded from the battery, while access may be readily had to said chamber and its battery by means of the sliding lid b'. Furthermore, the case is, in 45 the manner described, divided into three compartments—namely, the chamber B', closed by the lid b', the compartment B³ in the forward end of the case in front of the chamber B', and in which may be kept the detachable 50 parts of the apparatus, such as the current-ap-

plying wires or conductors and their handles, and the compartment B³ in the upper part of the case, above the cell-chamber, and communicating at its forward end with the chamber B².

Within the case in the space or compartment B³ above the cell-chamber I arrange the base or table C, of insulating material, and I adapt the same to be capable of sliding or moving horizontally by fitting its side edges 55 in ways b⁴, provided in or upon the side walls, b⁵, of the case. Upon the forward end of the sliding base C, and preferably on the under side thereof, I fix the magnet or coil C', which may be done by means of a frame or standards, c, as shown, the coil having the usual sliding current-graduator cylinder, C², upon it, as shown. When the base C is slid into the case, it is stopped against the rear wall, b⁶, thereof, and the coil, with its graduatore cylinder C² closed upon it, lies within the front 60 part of the case, as illustrated in broken lines in Fig. 2. When the base C is slid outward until the coil C' is brought beyond the line of the front edges of the side walls of the case, 65 the movement of the base is preferably stopped by a pin, c', fixed in the said base, impinging upon a stop, c², on the case-wall, as shown in Figs. 1 and 2. The stop c² is preferably a disengageable one—as, for example, a leaf-spring, as shown—so that it may be manipulated to permit the pin c' to escape or pass it, 70 in order that the sliding base C may be wholly withdrawn from its ways, whereby access may be had to the lid of the cell-chamber. 75

Upon the case-walls are contact-points d and d', to which the respective pole-wires a and a' lead from the battery-cell, as shown in Fig. 2, and upon the sliding base C are the contact-points c³ and c⁴, preferably in the form of leaf-springs, as shown, which are brought into contact with the points d and d', respectively, when the sliding base is slid outward to its limit of such movement, as described. This is plainly illustrated in Fig. 2. The points d and d' are preferably on the side walls of the case below the line of the sliding base, and the points c³ and c⁴ are therefore preferably on the under side of the said base, as shown. 85

At e and e' are shown the usual connecting 90

or circuit wires leading from the respective battery-poles through the points c^3 and c^4 to the magnet-coil, and these wires are preferably fixed on the under side of the base C.

5 D is the usual vibratory circuit-breaker carried by the base C, and preferably on the upper side thereof. At e^2 are shown the customary socket-terminals (numbered 1 2 3 in Fig. 1) of the current-wires from the magnet, 10 and to which the circuit-wires for applying the current to the person may be attached.

At B^4 is shown a gate, preferably arranged to swing vertically upon hinges about midway of the height of the front of the case, 15 and adapted to close the upper part of the front end or wall of the case.

B^5 is the top or lid of the case, hinged upon the top edge of the rear wall and adapted to close down over the chamber or compartment 20 B^3 , occupied by the sliding base and its attached parts, and desirably to fasten or clamp to the gate B^4 when the latter is closed.

By means of the case constructed as described, with its lid B^5 and gate B^4 , and the 25 sliding base C, carrying the described attached parts, when it is desired to put the battery in action for use, the sliding outward of the base C in its described ways will accomplish this result, and this result cannot be accomplished 30 without opening the case and swinging downward the gate B^4 . It will be noted that the graduator-cylinder C^2 on the magnet or coil can only be operated when the base has been slid outward, as described. When the case is 35 closed after the use of the apparatus, the shutting of the gate B^4 operates to slide the base C inwardly on its ways in the case, and thus to break contact at the points $a c^3$ and $a' c^4$, and hence stop the working of the battery or cell 40 A. The closing up of the case of the apparatus therefore acts automatically to stop the battery action, and the liability to leave the battery in action after use and subsequent to shutting its inclosing-case, as is liable to occur 45 in cases as now constructed, is wholly avoided, and economy in the battery is thus promoted.

E is a circuit-breaker or switch, which I mount upon the upper face of the sliding base C in the pole-wire leading from one of 50 the contact-points of the base to the coil, and preferably as shown in the wire e. By means of this circuit-breaker the action of the battery may be at any time stopped while the base is in its outwardly-extended position 55 without the necessity of sliding said base backward in its ways.

The base may be given a desirable frictional seat in its ways by means of a spring, c^5 , on its edge, as shown in Fig. 3.

60 What I claim as my invention, and desire to secure by Letters Patent, is—

1. In an electro-medical apparatus, the combination of the inclosing-case containing the battery or cell and provided with contact-points d and d' , an insulating-base, C, carrying a magneto-coil, C' , and contact-points c^3 and c^4 , in electrical connection therewith and adapted to slide in ways in said case and to project therefrom, with electrical connection established with the battery through said contact-points, and a gate, B^4 , adapted to close the side of the case through which said base projects, and in closing to swing to and impinge upon said base, substantially as and for the purpose set forth. 65 70 75

2. In an electro-medical apparatus, the combination of the case B, containing the battery or cell A and having the contact-points d and d' on the case-walls, the ways b^4 in said walls above said contact-points, the base C, adapted 80 to slide in said ways and to project beyond the case, the stop device $c^3 c^4$, to limit the outward movement of said sliding base, the coil C' and its graduator C^2 , carried on the projected end of said base, the contact-points c^3 85 and c^4 on said base and in electrical connection with said coil and adapted to engage the contact-points on the case when said base is slid outward, together with the gate B^4 , adapted to close the case where the said base 90 projects and to swing to and impinge upon the projected end of said base in closing, substantially as and for the purpose described.

3. In an electro-medical apparatus, the combination, with the walls of the inclosing-case, 95 of the partition b , extending laterally of the interior of the case and terminating vertically below the top of the case, and the sliding cover b' , working in ways in the case-wall and closing over the upper edge of said partition, together with the lid B^5 , whereby a chamber, B' , is constituted in the case adapted to inclose and shelter the battery-cell, and a chamber at one side and above said cell-chamber is constituted for the remaining operative 100 and detachable parts of the apparatus, substantially as set forth.

4. In an electro-medical apparatus, the sliding base C, carrying the magneto-coil C' and contact-points c^3 and c^4 , adapted to engage and 110 disengage contact-points of the battery inclosed in the case in which said base slides, in combination with a circuit-breaker, E, placed in a circuit-wire between one of the contact-points on the base and the magneto-coil, substantially as and for the purpose set forth. 115
